UNITED STATES PATENT OFFICE

CHARLES C. JAMIESON, OF JACKSONVILLE, FLORIDA

PULVERIZER

Application filed October 28, 1930. Serial No. 491,802.

This invention relates in general to road building machinery and more particularly has reference to an apparatus for pulverizing the natural aggregate of a roadbed to the desired depth for incorporation with a binder in the construction of mixed-in-place roads.

Previous to this time, in the construction of mixed-in-place roads, the roadbed has been graded, brought to level and cross section, then scarified or harrowed to prepare the roadbed for the application of such liquid binders as asphalts, coal tar, etc., after which the binders were mixed with the aggregate by means of disc harrows and grading machines and subsequently dragged or rolled.

An object of this invention is to provide an apparatus for breaking up the natural aggregates composing the roadbed.

Another object of this invention is to provide an apparatus for plowing a roadbed and breaking up the aggregate turned over by cutting, with provision for insuring pulverization by obstructing movement of the aggregate while undergoing cutting.

Still another object of this invention is to provide an apparatus for plowing a roadbed, breaking up of the aggregate turned over by cutting, with provision for securing pulverization by obstructing movement of the aggregate while undergoing cutting, and to thus insure the thorough incorporation of the asphaltic cement or other binder throughout the aggregate and the coating of the grains of the aggregate therewith.

A further object of this invention is to provide an apparatus for breaking up the natural aggregate composing the roadbed and to provide a baffle plate or guard to prevent the throwing of pulverized aggregate beyond the edge of the road, said baffle plate to form a guide, for the direction of the machine in use and to provide a means of working up to the edge of the road without scattering the treated material beyond the edges of the road onto the shoulders thereof.

With these and other objects in view which may be incident to my improvements, the invention consists in the parts and com-

bination to be hereinafter set forth and claimed, with the understanding that the several necessary elements comprising my invention may be varied in construction, proportions, and arrangement, without departing from the spirit and scope of the appended claims.

In order to make my invention more clearly understood, I have shown in the accompanying drawings, means for carrying the same into practical effect without limiting the improvements in their useful applications to the particular constructions which, for the purpose of explanation, have been made the subject of illustration.

I employ the apparatus forming the subject matter of my present invention to plow a roadbed in which it is desired to incorporate the natural aggregate thereof with a liquid binder such as asphalt. In the use of my novel apparatus, I first plow the surface to be treated whether it is intended to construct a new road or where an old pavement is to be torn up in order to lay a new surface.

In the drawings forming a part of this specification:

Fig. 1 is a side view of the apparatus forming the subject matter of my invention showing the adjustable baffle plates, and drag.

Fig. 2 is a top view of my apparatus showing the connections for operating the shafts carrying the blades, partly in plan.

Fig. 3 is a side view of a portion of the apparatus showing the plows and the relation of the shafts carrying the blades, and the grids, thereto.

Fig. 4 is a top fragmentary view partly in section taken on line 4—4 of section 3. 90

Fig. 5 is a sectional view of a shaft carrying the grids.

Fig. 6 is a top view of a grid taken on line 6—6 of Fig. 5.

Fig. 7 is a top view taken on line 7—7 of Fig. 5.

Fig. 8 is a sectional view taken on line 8—8 of Fig. 5.

Fig. 9 is a sectional view taken on line 9—9 of Fig. 1. 100

Fig. 10 is a sectional view taken on line 10—10 of Fig. 1.

As the roadbed is turned over by the plows provided on my apparatus the turned over material is directed from each plow into adjacent rotating blades operating on vertically mounted shafts.

Free passage of portions of the turned over material through the blades without 10 being broken up is positively prevented by the interposition of grids between the series of blades on each shaft so that besides the natural resistance in the blades offered by the inertia of the material, the grids positively 15 obstruct passage of the material not broken up sufficiently fine to pass between the spaces afforded by the grids and blades.

It will be appreciated that material fed into the blades would ordinarily be thrown 20 outward after passage therethrough. This is of course undesirable in the construction of a roadway as in plowing, as it tends to produce an uneven surface or to fill up adjacent furrows. I overcome this difficulty 25 by providing an angularly positioned baffle adjacent to the series of the aligned shafts carrying the blades so as to direct material thrown thereagainst downward, to fill the furrows as they are uncovered by the plows. 30 The baffle is vertically adjustable so that the plows may be lowered to varying depths without the baffles contacting with the surface operated upon. The bottom of the baffle is further provided with a hinged drag 35 to level the surface after the aggregate composing the same has been broken up. An additional baffle is provided on the apparatus, on the side thereof and in longitudinal alignment therewith, similarly vertically 40 adjustable, but not provided with a drag, to form an edge of the pulverized aggregate, by deflection of the same from the blades thereagainst.

Referring more particularly by numerals 45 to the drawings in which the same and similar elements are designated by like symbols of reference throughout and more especially to Fig. 1 my apparatus comprises a frame carrying a series of rotating blades having 50 stationary grids interposed therebetween, positioned between a series of stationary plows, and normally stationary baffle plates, mounted on wheels.

The frame as shown in Figures 1 and 2, particularly 55 2, comprises a side bar 1 having a socket 2 mounted on the rear end thereof for receiving the end of a curved axle 3 on which is mounted a trailing wheel 4. The front end of the side bar 1 is bent inwardly 60 as at 5, and outwardly as at 6 to provide a portion 7 on the front end parallel with the body portion 1 of the bar, connected to a longitudinal draw bar 8. The side bar 1 is additionally connected to the draw bar 8 65 through integrally formed angularly posi-

tioned cross braces 9 and 11. The draw bar 8 is further connected to a correspondingly positioned draw bar 12 through integrally constructed angularly positioned cross braces 13 and 14, intermediate the ends 70 of the same, and at the front end by a flanged transverse brace 15. The draw bars 8 and 12 are bent downwardly at 16, as shown in Fig. 1, and clevises 17 and 18 attached to the ends thereof for securing the 75 apparatus to a tractor or other vehicle.

The front portion of the apparatus is carried on wheels 19 and 21. The wheel 19 is mounted on a bent axle 22 which extends through the side bar 1, wherein a collar 23 is seated, and the end of the axle is fixed in the side of a longitudinal portion 24, formed integral with the angularly positioned cross braces 9 and 11 and fixed to the side of the draw bar 8 adjacent its rear end. 80 The wheel 21 is carried on an axle 25 which extends through a collar 26 supported on the frame by connection with an angular bar 27 fixed in a socket 28 formed integral with the collar, and extending through collars 29 and 31 seated in apertures provided in the draw bars 8 and 12. The axle 25 is additionally supported through a bar 32 having its respective ends seated in a socket 33 formed in the collar 26 in addition to the socket 28, and in a socket formed in the collar 29. The bars 27 and 32 are further rigidly held by a cross brace 34 formed with apertures adjacent each end for receiving the bars. 90

A plurality of plow shares 35, 36, and 37 are carried on the frame. The share 35, as shown in Fig. 3, is carried by a curved connecting arm 38 mounted on the side bar 1, the share 36 by a curved connecting arm 39 105 mounted on the draw bar 8 and the share 37 on a connecting arm 41 mounted on the draw bar 12, the shares being aligned and carried on the frame in angular relation thereto. 110

A plurality of vertical shafts 42, 43 and 44, as better shown in Fig. 4, are also carried by the frame. The shaft 42 is mounted on the end of an extension 45 integrally formed with the angular braces 9 and 11 115 and angularly positioned with respect to the side bar 1. The shaft 42, is fitted in a bearing 46 adjacent to the top, which is held to the end of the extension 45 by a strap 47. The shaft 43 fitted in a similar bearing 48 is mounted on the end of an extension 49 of the angular braces 13 and 14, likewise angularly positioned with respect to the side bar 1 and parallel with the extension 45, by a strap 51. The shaft 44, 120 also carried in a bearing 52, is mounted on the end of a brace 53 having the other end mounted on the draw bar 12, and positioned parallel with the extensions 45 and 49. 125

The shafts which are adapted to rotate, 130

are each provided with a series of blades 54 separated by spacers 55, and held against collars 56 fixed on the shafts adjacent to the top ends, and at the bottom ends by nuts 57 screwed on threaded extensions 58, more clearly shown in Fig. 3.

Sprocket wheels (not shown) are adapted to be keyed on the tops of the shafts for engagement by a flexible driving mechanism, 10 the shafts adapted to be rotated by engagement of a worm gear on the shaft 43, with a worm carried on a shaft 59 operating in a housing 61 which communicates with a tapered housing 62 surrounding the top of 15 the shaft 43. The tops of the shafts 42 and 44 are similarly incased in housings 63 and 64.

A casing 65 is seated on the tops of the 20 housings 62, 63, and 64, having apertures in the bottom thereof for receiving the tops of the shafts, the casing 65, receiving the sprocket wheels keyed on the tops of the shafts and the flexible driving mechanism connecting the same. The casing is adapted 25 to receive lubricant which may collect in the housings communicating therewith and thus result in efficient lubrication of the bearings in which the vertical shafts are operated, the casing being provided with a 30 removable cover 66 to prevent entrance of foreign material therein.

The shaft 59 operating the worm in the casing 61, to rotate the vertical shafts by engagement of the worm with the gear carried on the shaft 43, and the shafts 42 and 44 by engagement of the flexible driving mechanism with the sprockets carried thereby, is adapted to be operated through a universal toggle joint 67 by a shaft 68 which 40 may be operated by any suitable source of power such as by connection with the driving mechanism of a tractor. The mechanism herein described for rotating the blades is, of course, susceptible to modification, 45 and the invention is in no wise restricted to the particular construction described which manifestly is subject to wide variation.

The ends of the braces 45, 49, and 53, 50 forming a part of the frame and carrying the blade assemblies are connected by a side bar 69. The bar 69 is bent in the rear as at 71, for connection with the end of the extension 45 integrally formed with the cross braces 9 and 11. The bar is connected 55 to the ends of the braces 49 and 53 by angle irons 72 and 73, and is angularly bent at the forward end as at 75 and 76, forming an extension 77 transversely positioned with respect to the side bar 1, and connected to the 60 draw bars 8 and 12 by clamps 78 and 79.

While the mechanism thus far described is to some degree conventional, I propose to modify the structure by interposing stationary grids 81 between the blades 54 fixedly 65 carried by the rotating shafts 42, 43, and 44.

The grids 81, as clearly shown in Fig. 6, are preferably rectilinear in form, cut off at opposite corners as at 82, and 83, and formed with integral curved central extensions 84 and 85. The grids are provided with centrally located hexagonal apertures adapted to be fitted on a plurality of normally stationary vertically positioned shafts, as shown in Fig. 5, 86, 87, and 88. The shafts carrying the grids are fitted in collars 89, 91, 70 and 92 at the top, which are held on the side bar 69 by clamps 93, 94, and 95.

The clamps 93 and 94 extend through the side of the bar 69, holding the collars thereagainst, while the collar 92, formed to fit in the curved portion 75 in the front end of the bar, and to be held therein by the clamp 95 extending across the angle formed by the curved portion 75 of the bar. Each of the shafts is provided with transverse apertures 85 at the top adapted to coincide with transverse apertures provided in the collars for receiving shear pins 97, as shown in Fig. 8, for permitting rotation of the normally stationary shafts in the event of lodgment of 90 material unable to pass between the blades and grids, to prevent breaking of the same.

The grids 81 are spaced on the respective shaft, by spacers 98, secured by nuts 99 screwed on threaded extensions formed on 95 the bottoms of the shafts. The bottoms of the shafts are further provided with extensions adapted to fit in collars 101, 102, and 103, as shown in Fig. 3, which are held by straps, as shown in Fig. 7, 104, 105, and 106 100 formed integral with connecting arms 107, 108, and 109, which are connected at the top to the draw bar 8, and on each side of the draw bar 12, respectively.

Material thrown by the plow shares into 105 the rotating blades has been offered no resistance in the past, except the resistance existing by reason of the inertia of the material. The grids are intended to obstruct 110 passage of the material through the blades so as not to allow material of a size greater than the spaces between the grids and blades to pass, and thus insure the complete pulverization of material passing through the 115 blades and the intimate and substantially homogeneous incorporation of the components of the material.

Previous to this time the material passing through the blades without obstruction further than that of the resistance offered by 120 reason of the inertia of the material, has been thrown outward from the blades without deflection. I provide a vertically positioned baffle plate parallel with the shafts carrying the grids and blades and thus angularly arranged with respect to the frame 111, as shown in Figures 1, 2, 9, and 10, adjacent the blades, fixed to the side bar 69 of the frame by connecting arms 112, 113, and 114. The baffle plate is provided with 130

a plurality of vertical straps 115, 116, and 117, each formed with a pair of longitudinal slots 118 and 119, adapted to coincide with slots 121 and 122 provided on the face of the baffle plate for receiving a pair of bolts 123, and a pair of nuts 124 and 125, washers 126 and 127 fitting over the bolts under the nuts. The bolts extend through apertures provided on the connecting arms 112, 113, 10 and 114 provided for vertically adjusting the baffle plate.

The bottoms of the bands 115, 116, and 117 are formed with eyes adapted to receive pins 128 fitted in similar eyes formed on extensions of the straps 129, 131, and 132 which are secured on a drag 133 provided with a seat 134 at the bottom. The drag, hinged to the baffle plate, is adapted to smooth pulverized material deflected thereby, and as the same is pivotally carried by the baffle plate, to be vertically adjustable therewith. Supplemented baffle plate 135 is carried on a frame forward of the baffle plate 111, vertically positioned coextensive with the height of the baffle plate and drag there attached. Baffle plate 135 is attached to the frame by angular arm 136 secured on the side of the bar 69, and a connecting arm 137 held on the draw bars 8 and 12 by clamps 138 and 139, respectively. The baffle plate 135 is provided with reinforced edges 141 and 142 on the sides integral with reinforced edges on the top and bottom, each provided with a pair of aligned slots 143 and 144 coinciding with slots on the baffle plate, adapted to receive a pair of bolts 145, and a pair of nuts and washers 146 corresponding to those extending through the baffle plate 111, for a vertical adjustment of the baffle plate 135, in the same manner. The baffle plate 135, intended to deflect material thrown from the blades, to be subsequently smoothed by the drag 133 carried on the baffle plate 111, is also adapted to 45 form an edge of the pulverized material to align the side of the roadway.

Vertical adjustment of both baffle plates is provided for in order to allow the plow share to be extended to any desired depth, 50 without contact of the drag 133 or the baffle plate 135 with the surface operated upon.

The operation of my apparatus will be readily understood, the same being adapted to be attached to a motor drawn vehicle, 55 preferably a tractor, through the clevises 18 and 19. The shaft 68 adapted to rotate the blades 54 by a connection with the shaft 59 through the universal toggle joint 67, operating a worm in an engagement with a worm gear on a shaft 43 carrying sprocket wheels 60 carried by the shafts 42 and 44, through a flexible mechanism not shown, or by any other suitable drag, is adapted to be connected with a power take-off on the vehicle 65 by which the apparatus is drawn. Of course

if a powered vehicle is not available, the blades may be rotated by a power blade carried on the apparatus. In any event it is advisable to interpose a transmission between the source of power and the driving mechanism so that the speed at which the blade is rotated may be controlled to suit the particular requirements.

While the plow shares are not shown as adjustable it is intended that the same be capable of being lowered in any conventional manner to the depth to which it is desired to scarify the surface operated upon. The bottoms of the shafts carrying the rotating blades and the grids, need not necessarily be positioned on a plane with the bottoms of the shares, but on the contrary it is advisable that the same terminate above the bottoms of the shares as shown in the drawings, in any event not extending below the same. The material turned up by the plow shares is directed into the rotating blades where passage of the same therethrough is obstructed by the grids.

In this manner pulverization of the material is insured as the particles must be at least fine enough to pass between the spaces afforded between the spaces and the grids. In the event of lodgement of material unable to pass between the grids and blades, therebetween the pins or the shafts carrying the grids stationary are adapted to be sheared so that the grids may be allowed to rotate by reason of such force, and prevent breakage of either the blades or the grids.

My apparatus is particularly adaptable as has been previously stated, to the mixing and thorough incorporation of a binder such as asphalt with the natural aggregate of a roadway, preferably previously pulverized by working with my apparatus in the manner set forth.

The pulverized material thrown outward by the blades is adapted to be deflected onto the surface operated upon by the forward and lower baffle plates positioned adjacent to the grids and the blades. The baffle plates may be adjusted so that the forward baffle plate will approximately contact with the surface so as to form an edge, and thus align a roadway if such is being operated upon, and the rear drag carried by the rear baffle plate similarly positioned so as to smooth the pulverized material deflected by both baffle plates.

There is accomplished by this invention an apparatus for plowing and finely breaking up the material turned over, particularly for plowing up the natural aggregate composing a roadbed, constructed to insure the complete pulverization of the aggregate and to smooth and form an edge of the same so as to prepare the aggregate for incorporation with a binder, and to subsequently aid in incorporating the binder with the

aggregate by working over of the mixture of aggregate and binder through the blades.

While I have shown and described the preferred embodiment of my invention, I wish it to be understood that I do not confine myself to the precise details of construction herein set forth by way of illustration, as it is apparent that many changes and variations may be made therein, by those skilled in the art without departing from the spirit of the invention, or exceeding the scope of the appended claims.

I claim:

1. A pulverizer comprising vertically mounted rotating blades, means to direct packed earth into said blades, and means to obstruct passage of the earth through the blades.

2. A mixer comprising vertically mounted rotating blades, means to plow and turn over pulverized aggregate into said blades, and grids interposed between the blades to obstruct the passage thereof through the blades to thoroughly mix the components.

3. A pulverizer comprising vertically mounted rotating blades, means to plow and turn over earth into said blades, and stationary grids interposed between the blades to obstruct the passage of earth therethrough.

4. A pulverizer comprising means to plow and turn over the earth, vertically rotating blades having grids interposed therebetween to obstruct passage of the earth, and means to deflect and smooth the earth pulverized.

5. A pulverizer comprising means to plow and turn over a pulverized aggregate, vertically rotating blades having grids interposed therebetween to obstruct passage of the aggregate through the blades, and means to deflect the pulverized mix for forming an edge, and means to smooth the surface treated material.

6. A pulverizer comprising vertically mounted rotating blades, means to plow and turn over earth into said rotating blades, means normally stationary to obstruct passage of the earth through the blades, and means to allow movement of the obstructing means upon lodgment of unbreakable material between the same and the blades.

7. A pulverizing mixer for incorporating a binder application on a pulverized aggregate, therewith, comprising vertically mounted rotating blades, means to plow and turn over the binder and aggregate into said rotating blades, normally stationary grids mounted between the blades to obstruct the passage thereof through the blades and insure thorough mixing of the same, and means to allow movement of the grids upon the lodgment of unbreakable material between the grids and the blades.

8. A pulverizer comprising a frame, a plow share carried by the frame, a vertical rotatable shaft carrying horizontally positioned blades, mounted on the frame adjacent the plow share and a stationary shaft carrying fixed grids interposed between the blades, mounted on the frame adjacent the shaft carrying the blades. 70

9. A pulverizer comprising a frame, a plurality of aligned plow shares mounted on the frame in angular relation thereto, a plurality of vertical rotatable shafts carrying horizontally positioned blades, mounted on the frame adjacent the plow shares and parallel thereto, and a plurality of stationary shafts carrying fixed grids interposed between the blades mounted on the frame adjacent the shafts carrying the blades and in alignment therewith. 75

10. A pulverizer comprising vertically mounted rotating blades, means to plow the constituents of a roadbed into said rotating blades, means to obstruct passage thereof through the blades, pulverize and mix the same, and a baffle plate positioned adjacent the blades to deflect the pulverized mix, a drag on the baffle plate to smooth the product, and a baffle plate positioned forward of the plate carrying the drag to form an edge of the material, both baffle plates being vertically adjustable to allow adjustment of the plows to the desired depth. 85

11. A pulverizer comprising a frame, a plurality of aligned plow shares angularly mounted on the frame, a plurality of vertical rotatable shafts carrying horizontally mounted blades positioned adjacent the plow shares in parallel relation thereto, a plurality of vertical shafts carrying fixed grids interposed between the blades, positioned in alignment with the shafts carrying the blades, and held stationary by shear pins, a vertically adjustable baffle plate mounted on the side of the frame adjacent the shafts carrying the blades and grids, a drag 100 weighted at the bottom, and a vertically adjustable baffle plate positioned in longitudinal relation with the frame, mounted thereon forward of the baffle plate carrying the hinged drag. 105

12. A pulverizer comprising vertically mounted rotating blades, means to direct earth into said rotating blades, means to obstruct the passage of the earth through the blades, means to successively deflect the pulverized mix and form an edge thereof and means to smooth the pulverized mix. 110 120

In testimony whereof I affix my signature.

CHARLES C. JAMIESON.
